UNITED STATES PATENT OFFICE.

ALBERT E. COOK, OF EVANSTON, ILLINOIS.

CORRUGATED AUTO MARINE VEHICLE.

Application filed January 22, 1927. Serial No. 162,757.

This invention relates to an auto marine vehicle or land and water craft constructed to afford great strength by producing the hull and pontoons of corrugated metal.

5 It is an object of this invention to provide a land and water craft wherein the hull and the pontoons therefor are both constructed of corrugated sheet metal to permit the corrugated pontoons to lockingly interfit in the 10 corrugated pockets formed in the sides of the corrugated vehicle hull.

It is an important object of this invention to provide an auto marine vehicle wherein the hull or body is constructed of corrugated 15 metal to afford a hull of great strength and one wherein the pontoon pockets formed in the side of the hull, also being corrugated, permit the corrugated pontoons movably mounted on the sides of the hull to lockingly 20 interfit the same, in either the raised or lowered positions of the pontoons.

Other and further important objects of this invention will be apparent from the disclosures in the specification and the accompanying 25 drawings.

This invention, in a preferred form, is illustrated in the drawings and hereinafter more fully described.

On the drawings:

30 Figure 1 is a side elevation of a corrugated auto marine vehicle embodying the principles of this invention.

Figure 2 is an enlarged vertical transverse section taken on line II—II of Figure 1.

35 Figure 3 is an enlarged fragmentary detail section of the hinge and pontoon taken on line III—III of Figure 2.

Figure 4 is an enlarged fragmentary detail section of the pontoon hinge and the 40 hull taken on line IV—IV of Figure 2.

Figure 5 is an enlarged fragmentary detail section taken longitudinally through a portion of the hull on line V—V of Figure 2.

Figure 6 is an enlarged section of the deck 45 of the hull taken on line VI—VI of Figure 2.

As shown on the drawings:

The improved auto marine vehicle of this invention comprises a hull constructed of corrugated sides 1, a corrugated deck 2 and 50 a corrugated bottom 3. The corrugations are drawn to a point or lesser dimension in forming the bow, stern and other diminished areas, thus affording great strength and eliminating largely the twist tendency in the 55 metal. While the deck or roof of the auto

marine hull is shown as being transversely corrugated, said deck may be constructed with the corrugations disposed diagonally to produce lateral strength to resist twist tendency without the use of reinforcing ribs. 60 The corrugated bottom 3 affords runners without the need of protecting strips, with the runners serving as a means to reduce friction and wear when effecting a landing. The sides of the hull are provided with 65 upper corrugated pontoon pockets 4 and lower corrugated pontoon pockets 5. The interior of the hull is provided with T cross sectioned ribs or braces 6 to afford a strong framework for the corrugated hull. Mounted on top of the deck 2 is a vehicle top 7 of any desired construction. Rigidly secured 70 on each side of the hull at the line of intersection between the upper and lower pontoon pockets 4 and 5 are a plurality of spaced 75 links or hollow supports 8 which support a hollow hinge tube or shaft 9 on which spaced link members or sleeves 10 are pivotally engaged, in alternate relation with the hinge links 8.

The hinge sleeves 10 are secured longitudinally in a line on a corrugated pontoon 11 one of which is disposed on each side of the vehicle hull. Each of the corrugated pontoons 11 is provided with a cylindrical 85 intermediate section and tapering closed ends, as clearly illustrated in Figure 1. The interior of each of the pontoons 11 is reinforced by metal ribs or hoops 12. As illustrated in Figures 1 and 2 the auto marine vehicle is provided with rear driving 90 wheels 13 and steering wheels 14.

If desired the corrugated plates forming the hull may be arranged to inter-lap along the pontoon hinge lines to form a construction of double strength along the hinge lines. Parts of the overlapping margins of the plates may be used to form parts of the 95 hinges.

The adjustable pontoons 11 may be moved 100 from their lower position in which they are lockingly engaged with the corrugations of the lower pockets 5, into their upper positions by any suitable mechanisms, permitting the pontoons when raised to pivot about 105 the hinge shaft 9 until the corrugations of the pontoons lockingly seat in the corrugations of the upper hull pockets 4. The pontoons when adjusted may be secured in their respective hull pockets by any suitable 110

means with said pontoons having a tight fit with the hull pockets to afford an improved water craft, of particularly strong and durable construction, and able to withstand heavy seas when the vehicle is used in the water. If desired, all the exposed walls of the vehicle may be constructed of corrugated metal properly reinforced by brace ribs of any desired construction.

10 The improved hull by being constructed of corrugated sheet metal affords a surplus of metal permitting repairs to be easily made in case the hull becomes jammed or bent. The inner grooves of the hull, formed by the 15 corrugations in the metal, may be filled with rubber compound or any suitable deadening substance to retard sound and also make the hull waterproof.

I am aware that many changes may be 20 made, and numerous details of the construction may be varied through a wide range without departing from the principles of this invention, and I therefore do not purpose limiting the patent granted hereon, 25 otherwise than necessitated by the prior art.

I claim as my invention:

1. An auto marine vehicle comprising a corrugated hull and corrugated pontoons mounted thereon and tapered at the ends, 30 said pontoons having the corrugations extending the full length thereof with the end portions of the corrugations tapered.

2. An auto marine vehicle comprising a longitudinally corrugated hull, a transversely 35 corrugated top, wheels for supporting the hull, and corrugated pontoons mounted on the side of the corrugated hull, said pontoons having tapered ends provided with tapered corrugations.

40 3. An auto marine vehicle comprising a corrugated hull, having corrugated pockets formed in the sides thereof, corrugated pontoons disposed on opposite sides of the hull and hinge means for pivotally supporting 45 said corrugated pontoons in position to seat in said corrugated pockets.

4. In an auto marine vehicle the combination 50 with a corrugated hull having corrugated pockets therein, of tapered and corrugated pontoons pivotally mounted on the hull to lockingly interfit said pockets.

5. In an auto marine vehicle the combination 55 with a hull having pontoon pockets formed therein, of corrugated pontoons pivotally mounted on said hull adapted to seat in said pockets.

6. In an auto marine vehicle of the class 60 described, the combination with a corrugated hull having corrugated pockets formed therein, of corrugated pontoons pivotally mounted on said hull intermediate the pockets to permit the corrugated pontoons to be

lockingly seated in interfitting relation in said pockets.

7. An auto marine vehicle comprising a 65 corrugated hull, reinforcing ribs mounted therein, said hull having corrugated upper and lower pontoon pockets formed in the sides thereof, hinge members secured on each side of the hull at the line of intersection of the upper and lower pockets, corrugated pontoons disposed on opposite sides of the hull, and hinge means for pivotally connecting said corrugated pontoons with said hinge members to permit the corrugated pontoons to lockingly interfit in the corrugations of either the upper or lower pontoon pockets of said hull.

8. A water craft comprising a corrugated hull, and corrugated means adjustably 80 mounted thereon to vary the draft thereof and lockingly interfit with the corrugations of said hull.

9. A water craft comprising a longitudinally corrugated hull, a transversely corrugated deck therefor, said hull having corrugated upper and lower pockets formed in the sides thereof, hinge means connected with the exterior of the hull between the pockets on each side thereof, longitudinally corrugated hulls connected to said hinge means adapted to lockingly interfit with said corrugated pockets, said pontoons having tapered closed ends provided with tapered corrugations which are continuations of the longitudinal corrugations of said pontoons.

10. A water craft comprising a hull having corrugated pockets formed in the sides thereof, a plurality of spaced links rigidly secured on the sides of said hull, a tubular shaft supported by said links on each side of the hull, a tapered pontoon positioned on each side of said hull and having corrugations formed longitudinally thereon and extending the full length of the pontoon with the ends of said corrugations tapered to meet at the ends of the pontoon, and spaced sleeves integrally formed on each of said pontoons and pivotally engaged on one of said tubular shafts to pivotally support the pontoon in position and lockingly interfit in the corrugations of one of said pockets.

11. A water craft comprising a corrugated hull, hinge members connected to the sides thereof, said hull constructed with the corrugated plates thereof arranged to interlap along the hinge lines, and corrugated pontoons connected to said hinge members adapted to lockingly interfit with the corrugations of said hull to hold the pontoons 120 in position.

In testimony whereof I have hereunto subscribed my name.

ALBERT E. COOK.
